[57] CLAIM

The ornamental design for a motor mount for model
aeroplanes, as shown.

DESCRIPTION

FIG. 1 is a perspective view of a motor mount for
model aeroplanes showing my new design;

FIG. 2 is a front elevation view thereof;

FIG. 3 is a left side elevational view thereof;

FIG. 4 is a top plan view thereof; and

FIG. 5 is a bottom plan view thereof.

*FIG. 1.**FIG. 2.**FIG. 3.**FIG. 4.**FIG. 5.*
